(57) **CLAIM**

The ornamental design for a drone, as shown and described.

DESCRIPTION

FIG. 1 is a front perspective view of a drone showing my design.

FIG. 2 is a rear perspective view of the drone in FIG. 1.

FIG. 3 is a bottom perspective view of the drone in FIG. 1.

FIG. 4 is a front elevation view of the drone in FIG. 1.

FIG. 5 is a rear elevation view of the drone in FIG. 1.

FIG. 6 is a left side elevation view of the drone in FIG. 1.

FIG. 7 is a right side elevation view of the drone in FIG. 1.

FIG. 8 is a top plan view of the drone in FIG. 1.

FIG. 9 is a bottom plan view of the drone in FIG. 1.

FIG. 10 is an enlarged view of a portion of the drone labeled 10 in FIG. 1.

FIG. 11 is an enlarged view of a portion of the drone labeled 11 in FIG. 1.

FIG. 12 is an enlarged view of a portion of the drone labeled 12 in FIG. 1.

FIG. 13 is an enlarged view of a portion of the drone labeled 13 in FIG. 1.

FIG. 14 is an enlarged view of a portion of the drone labeled 14 in FIG. 1.

FIG. 15 is an enlarged view of a portion of the drone labeled 15 in FIG. 1.

FIG. 16 is an enlarged view of a portion of the drone labeled 16 in FIG. 1.

FIG. 17 is an enlarged view of a portion of the drone labeled 17 in FIG. 3.

FIG. 18 is an enlarged view of a portion of the drone labeled 18 in FIG. 3.

FIG. 19 is an enlarged view of a portion of the drone labeled 19 in FIG. 3.

(Continued)

FIG. 20 is an enlarged view of a portion of the drone labeled 20 in FIG. 3.

FIG. 21 is an enlarged view of a portion of the drone labeled 21 in FIG. 3.

FIG. 22 is an enlarged view of a portion of the drone labeled 22 in FIG. 3.

FIG. 23 is an enlarged view of a portion of the drone labeled 23 in FIG. 3.

FIG. 24 is an enlarged view of a portion of the drone labeled 24 in FIG. 3; and,

FIG. 25 is an enlarged view of a portion of the drone labeled 25 in FIG. 3.

The broken lines illustrate portions of the drone that form no part of the claimed design, as well as the extents of the enlarged drawing views.
